TYPEWRITER FEED ROLL AND THE LIKE

Richard O. Miller, West Hartford, Conn., assignor
to Underwood Elliott Fisher Company, New
York, N. Y., a corporation of Delaware

Application May 2, 1939, Serial No. 271,259

6 Claims. (Cl. 197—138)

This invention relates to rolls for typewriting machines and the like, such as are used for feeding and holding the paper around the typewriter platen.

5 A typewriter carriage in use requires almost continuous movement either in a step-by-step letter-feeding advance or in return to line starting position, and therefore minimum weight of the carriage is desired. The use of paper feed 10 rolls in multiple on a single machine, as many as eight being preferred in the standard Underwood typewriter, makes both light weight and economy in construction of these rolls important desiderata, to be attained, however, without 15 forfeiting the accuracy required in the function of the rolls in maintaining alignment of the paper.

It is accordingly one of the objects of the 20 present invention to provide a durable feed roll of light weight which shall be reliably operative in the performance of its functions, and particularly adapted for economic fabrication and assembly.

25 Typewriter feed rolls usually comprise an outer cylinder or tire of resilient frictional material such as rubber, installed on a core which provides bearings for rotatably supporting the roll on a shaft. For ease of assembly, it is desirable 30 that the periphery of the core present an even cylindrical surface for reception of the tire. It is, therefore, a further object of this invention to provide a feed roll core presenting a plain periphery and which may be fabricated of uniform sections interlocking with each other to 35 form a composite feed roll in association with the outer cylinder, the latter holding the parts in secure assembly notwithstanding the absence of flanges or other projecting members on the periphery of the core.

40 In its more specific aspect, the invention provides a feed-roll core that may be fabricated of uniform sections, together forming a cylinder of hollow construction to provide end bearings for the roll-mounting shaft, the core sections being especially adapted for manufacture by die-molding of a plastic material, such as Bakelite, enabling the use of simple, inexpensive molds, notwithstanding the hollow structure of the 45 composite roll core.

50 Other objects and advantages will hereinafter appear.

In the drawing:

55 Figure 1 is a perspective view of a portion of a typewriter carriage unit, illustrating a platen

and associated feed rolls representing a typical use of the invention.

Figure 2 is an exploded perspective view of the feed roll embodying the invention,

Figure 3 is a side elevation of the feed roll 5 mounted on a shaft, portions of the roll being broken away in central section, and

Figure 4 is a transverse section taken on a line 4—4 of Figure 3.

The numeral 5 indicates generally a feed roll 10 core which, in accordance with the invention, comprises a pair of complementary interlocking sections 6, 7. The complete feed roll may include an outer cylindrical member or tire 8 usually of resilient, frictional material such as 15 rubber, and having an internal bore 9 of a diameter approximating the diameter of the composite core 5, and adapted to be assembled therewith by axially sliding same over the interlocking core sections to the position shown in 20 Figure 3.

Paper feed rolls, in their conventional use in a typewriter, as illustrated in Figure 1, are rotatably supported on a shaft 10 and are usually arranged in multiple on a single shaft, as 25 shown, for cooperation with a typewriter platen 11. Each series of aligned rolls are yieldably pressed into contact with the platen 11 by suitable means, so that during feeding of the paper around the platen 11, the feed rolls serve to hold 30 the paper against the platen and maintain alignment of same during typing.

The rotatable mounting of a feed roll on the shaft 10 is afforded by providing journals 13 preferably at each end of the roll core, each 35 journal 13 having a bore fitting the shaft 10. In order to limit the bearing length of the journals 13 to the end portions only of the roll, it is desired that the roll core 5 be of hollow form presenting an intermediate internal bore 40 14 of a diameter larger than the shaft 10 and of substantial length.

To permit the molding of each core section 6, 7 in a mold of simple character without necessitating the use of separate, movable mold members, such as may be required to form the internal bore 14, and at the same time provide a solid integral end portion 15 for each of the journals 13, it is desirable that the core sections 6, 7 have a meeting or junctural line confined 50 within an intermediate length of the core. It is also desired that the core sections 6 and 7 be identical in size and shape so that both may be cast from the same mold, and the composite core may thus comprise merely two identical 55

products of the same mold. In accordance with the invention, each core section is formed of a homogeneously integral mass and includes a cylindrical end portion 15 forming the journal 5 13, and an elongate channel portion 16 integral with the end portion 15 and providing the internal bore 14 in the assembled core. It will be noted that when the two core sections 6, 7 are assembled to form the composite core, the ends 10 17 of each channel portion 16 abut the inner wall of the end portion 15 of the other core section, and the longitudinal edges 18 of each channel portion 16 also abut each other in matching relation. For simplicity of form, the 15 longitudinal meeting edges of the channels 16 are disposed substantially parallel with the axis of the core.

As shown in Figure 3, when the feed roll is assembled with its two core sections 6, 7 together 20 and the outer cylinder or tire 8 over the periphery of the core, the tire 8 holds the two core sections against radial separation from each other. The endwise or axial displacement of these core sections is prevented by an interlocking at the edges 18 of each section. This effect is accomplished by making each edge 18 somewhat irregular in form, that is, by having the line of separation of the two channels 16 arranged generally in a direction longitudinal of the core, 25 but in a sinuous or irregular path preferably symmetrically of the core. In the embodiment herein illustrated, each edge 18 is composed of two half lengths, each half being offset from the other to form a step or interlocking shoulder 20. 30 To maintain identity of the core sections 6, 7, the offset of the respective halves of each edge 18 are displaced equidistantly from a diametrical plane of the core 5, as shown more clearly in Figures 3 and 4. In that the offset or shoulder 35 19 is at the longitudinal middle of the edge 18, the identity of each core section is further maintained. In other words, with reference to each channel portion 16, it may be said that same are so formed that each is a complement of the other 40 and, together with their integral end portions 15, complete a cylindrical roll core having solid journals at each end and an intermediate bore.

Because of the elastic character of the rubber tire 8 which is installed on the core under a slight 45 tension, the core sections 6, 7 are held in accurate registry with each other and, in view of the interlocking relation of the core sections, endwise displacement is prevented and the feed roll is maintained dependably in its composite form. 50 It may be desired, to further assure permanent assembly, to affix the tire 8 in place by the use of a suitable adhesive while installing same on the core, the adhesive being preferably applied to the periphery of the assembled core 5 just before inserting same into the tire. It has been found 55 that the adhesive thus applied penetrates into the interstices of the junctural line between the two core sections so that when the adhesive has congealed, the effect of a solid roll structure is had. 60 Although in the specific embodiment herein illustrated, the invention is shown as being applicable to the feed rolls of a typewriter, it will be understood that the invention may be modified and embodied in other structures of similar character, without departing from its spirit or the 65 scope of the appended claims.

What is claimed is:

1. In a feed roll for typewriters, a roll core comprising a pair of complementary sections meeting each other at junctural areas, each of said sections including a cylindrical end portion and an integral, substantially semi-cylindrical portion, the junctural areas of said semi-cylindrical portions having correspondingly formed interlocking members.

2. A feed roll for typewriters, comprising a hollow roll core including a pair of complementary sections meeting each other at junctural areas, each section including a cylindrical end portion and an integral channel portion extending intermediate and longitudinally of said roll, the junctural edges of said channel portions having correspondingly formed interlocking members holding said sections against endwise displacement, and an outer cylinder embracing said core and holding said sections against radial displacement.

3. A feed roll for typewriters, comprising a hollow roll core including a pair of complementary sections meeting each other at junctural areas, each of said sections including a cylindrical end portion and an integral channel portion extending intermediate and longitudinally of said roll, the longitudinal edges of said channel portions abutting each other and being directed in a sinuous path symmetrical of said core and holding said sections against endwise displacement and an outer cylinder embracing said core and holding said sections against radial displacement.

4. A feed roll for typewriters, comprising a hollow roll core including a pair of complementary, uniform sections, each of said sections being homogeneously integral and including a cylindrical end portion, and an elongated channel portion extending intermediate and longitudinally of said roll, the longitudinal edges of each channel portion defining half lengths offset from each other and presenting a locking shoulder midway of said edge, the longitudinal channel edges of said sections meeting each other and interlocking to prevent endwise relative displacement, and an outer cylinder embracing said core and holding said sections against radial displacement.

5. In a feed roll for a typewriter, a composite feed roll bushing comprising two separable, diametrically opposite substantially semi-cylindrical sections having each an integral full cylinder end, said cylinder ends constituting the opposite ends of the composite bushing, interlocking means for opposing relative axial displacement of said members in either direction, and a feed roll tire embracing the composite bushing and holding its sections concentrically together.

6. In a feed roll for a typewriter, a composite feed roll bushing comprising two axially spaced cylindrical end-members having each a part-cylindrical extension forming a part of the composite bushing intermediate the cylindrical portions of the end-members, interlocking means for opposing relative axial displacement of said members in either direction, and a contractile feed roll tire embracing the composite bushing and holding its sections concentrically together.

RICHARD O. MILLER.
